[57] **CLAIM**

The ornamental design for a cleat fixable to the toe rail of a boat for attaching a spring line, as shown and described.

DESCRIPTION

FIG. 1 is a front perspective view of a cleat fixable to the toe rail of a boat for attaching a spring line, showing my new design;

FIG. 2 is a rear elevational view thereof;

FIG. 3 is a top plan view thereof;

FIG. 4 is a front elevational view thereof;

FIG. 5 is a bottom plan view thereof;

FIG. 6 is a right side elevational view thereof, the left side view being a mirror copy of this view; and,

FIG. 7 is a front elevational view thereof, in use of a boat. The broken line showing of a portion of a boat is for illustrative purposes only and forms no part of the claimed design.
